UNITED STATES PATENT OFFICE.

EDWARD PRENDERGAST, OF ST. LOUIS, MISSOURI.

GRADING MACHINE.

1,421,559.

Specification of Letters Patent.

Patented July 4, 1922.

Application filed May 10, 1920. Serial No. 380,019.

To all whom it may concern:

Be it known that I, EDWARD PRENDERGAST, a citizen of the United States, and resident of St. Louis and State of Missouri, have invented certain new and useful Improvements in Grading Machines, of which the following is a specification containing a full, clear, and exact description, references being had to accompanying drawings, forming a part thereof.

My invention relates to improvements in road graders and has for its primary object a road grader in which the cutter blades are formed in sections so that by removing one or more sections from either side roads of various widths can be graded. A further object is to construct a road grader which can be adjusted to grade different widths of road without changing the shape of the frame carrying the cutter blades and which can also be regulated so as to cut either a straight, a crowned or a concave road base, and which can also be so adjusted as to leave the shoulders which lead to the draining ditches either horizontal or inclined.

In the drawings:

Fig. 1 is a top plan view of my device.

Fig. 2 is a front elevation.

Fig. 3 is a side elevation with parts broken away and in sections.

Fig. 4 is an enlarged cross-sectional view of one of the side members.

Fig. 5 is an enlarged top plan view with one of the cutter blades removed and showing by dotted lines the manner of varying the width of cut.

Fig. 6 is an enlarged cross-sectional view of the frame after the cutter blade has been removed and showing the manner of attaching the filler blocks.

Fig. 7 is a side elevation of the spreader arm showing its adjusting features.

Fig. 8 is a perspective view of one of the filler plates made use of, and 9, 10, 11 and 12 are diagrammatic views showing the various types of grading accomplished by my device.

In the construction of my device I employ an A frame composed of channel bars 14, which are set on edge and secured together at their apex as at 15. On the upper edge of these channel bars are securely bolted the boxes or channels 16 through which the axles 17 and 18 pass. On the outer ends 55 of these axles the front wheel 19 and rear

wheels 20 are secured, these wheels being for the purpose of regulating the depth of cut made. To the upper edge of the channels 14 are also secured the boxes or bearings 21 through which an axle 22 passes, 60 and on this axle and between the members 14 is mounted the sectional roller 23, the purpose of this roller being to smooth out and pack a portion of the graded road. On the rear end of the members 14 is a plate 65 24 which is provided with a plurality of openings 25, these openings being for the purpose of adjustably securing the frames 26 thereto, these frames having journals or boxes 27 secured to their upper faces, which 70 carry the axle 28 and on this axle the sectional roller 29 is secured. This sectional roller has its outer section 30 provided with a projecting flange 31. This projecting flange will have a tendency to prevent 75 side shifting of the grader while being drawn over the road. The wheels 19 and 20 are likewise provided with a projecting rib 32 which is for the same purpose. All of the journals are secured to the frames by 80 means of bolts 33. My object in thus securing the journals or boxes is to permit the insertion of filler plates 34. This insertion of filler plates will regulate the depth of cut. In order to hold the frame in rigid 85 position the brace rods 35 are employed. These rods extend from one channel to the other and in connection with the plate 24 assist in making the frame rigid and non-collapsible. To the bottom of the channels 90 14 are bolted a plurality of short channels 36 to which the cutter blades 37 are secured. The channels 14 and 36 are held together by means of bolts 38 and when it is desired to vary the width of the road the desired 95 number of sections 36 can be removed. This is clearly shown in Fig. 5. Secured to the channels 14 are a pair of eyes 39 in which a short shaft 40 is secured and on this shaft 40 and between the eyes 39 is an eye 100 41 which is held in any desired position on the shaft 40 by means of a set-screw 42. Secured to the eye 41 is a section of angle iron 43 to which is pivotally attached a plate 44, this pivotal attachment being at 105 the point 45. The end of the plate 44 opposite the pivot 45 is provided with a slot 46 through which a bolt 47 passes. This pivot and slot arrangement is for the purpose of forming the inclined shoulders as shown in 110

Figs. 11 and 12, the channel 43 and plate 44 forming what is commercially known as a spreader arm and its inclination to the frame is controlled by means of the turn 5 buckles 48. When one section of the cutter blade and its support has been removed, it is necessary to fill up the space thus left with filler blocks 48^a so as to bring the bottom edge of the open space on a level 10 with the point 49 of the spreader arm. These filler blocks are secured to the channels 14 by means of the bolts 50. On the front of the frame is secured a perforated plate 51 which is provided with a plurality 15 of perforations 52 so that the grader can be made either to have a straight pull or a downward pull and prevent the point 15 from having a tendency to jump upward. When it is desired to lower the cutting edges 20 or make a deeper cut in the road the bolts 33 are removed and filler plates inserted under the channels or boxes 16, 21 and 27, thus bringing the wheels 19 and 20 and the rollers 23 and 24 farther away from the 25 cutting edge. If found desirable or necessary I may also attach brace rods 35 to the sections 36. These brace rods would, of course, be removed with their respective sections when making a narrow road, while 30 the brace rods secured to the members 14 will constantly remain in position.

It will be noted that by my construction I can grade a narrow road without changing the shape of the frame as has been hitherto 35 the common practice. I am thus enabled to make my frame stronger and more rigid and still at the same time grade roads of various widths. This has been found especially desirable in the construction of roads 40 wherein the center portion is made of concrete or other hard material while dirt is left on either side, because sometimes the concrete portion of the road is only made wide enough for one vehicle while in others 45 it is made wide enough for two vehicles to pass.

Having fully described my invention, what I claim is:

1. A grading machine comprising an A frame formed of channels, a plurality of 50 cutter blade sections secured to the underside of the said frame, wheels adjustably carried by the frame and rollers adjustably carried by the frame, and a cutter blade mounted on each side of the rear end of the 55 frame.

2. A grading machine comprising an A shaped frame, a plurality of cutter sections secured to the under side of each leg of the frame, wheels carried by said frame, filler 60 blades adapted to be placed on the frame for regulating the depth of cut, a roller mounted between the legs of the frame and a pair of rollers mounted at the rear of the frame, said rollers being capable of adjustment with respect to the depth of cut, and an adjustable cutter blade mounted on each side of the rear end of the frame. 65

3. A grading machine comprising an A frame, a plurality of sections secured to the 70 under side of the said frame, cutter blades carried by said sections, wheels adjustably carried by the frame and rollers adjustably carried by the frame, a spreader arm secured to the end of each side of the frame. 75

4. A grading machine comprising an A frame, a plurality of sections secured to the underside of the said frame, cutter blades carried by said sections, wheels adjustably carried by the frame and rollers adjustably 80 carried by the frame, a spreader arm secured to the end of each side of the frame, a cutter blade carried by said spreader arms, said cutter blade being adjustably mounted on one end so as to cut an inclined shoulder. 85

In testimony whereof, I have signed my name to this specification, in the presence of two subscribing witnesses:

EDWARD PRENDERGAST.
